WELL AGITATOR

Joseph H. Notley, Oklahoma City, Okla., assignor
of one-half to Arthur Thatcher, Oklahoma City,
Okla.

Application July 18, 1939, Serial No. 285,183

5 Claims. (Cl. 166—20)

This invention relates to an improved oil well agitator tool, and a particular object of the invention is to provide a device capable of being suspended and reciprocated in a well hole by attachment to the drill stem, in order to wash or clean the walls of an oil well hole.

Another object of the invention is to provide a device for utilizing the fluid in the well hole for washing the sand, paraffin, and the like, from the walls of the well hole into the oil pool.

And still another important object of the invention is to provide a well agitator of such construction that it sprays oil from the oil pool against the wall of the hole in order to wash loose sand, and the like, down into the oil pool, so that it can be bailed out in any conventional manner.

Other objects and advantages of the invention will be evident from the following detailed description read in conjunction with the accompanying drawing which illustrates one form of my invention.

In the drawing:

Fig. 1 is an elevational view of the invention, and,

Fig. 2 is a vertical elevation view of the invention shown disposed in an oil well hole.

Fig. 3 is a detail view disclosing a modified construction of the annular grooves.

Referring to the drawing in detail, the improved oil well agitator comprises a cylindrical barrel or plunger 10, provided at its upper end with threads 12 for attachment to a drill stem (not shown) in order to suspend the barrel 10 in the bottom of an oil well hole 14. The barrel 10 is formed of steel or any similar metal, and may be of any length or diameter desired, and preferably consists of an upper portion 13 attached at 15 to the hollow barrel 10 for a purpose to be hereinafter set forth. The outer periphery of the barrel 10 is provided with a plurality of vertical or axially spaced annular grooves 16 for a purpose as will be hereinafter referred to.

The lower end of the barrel is rounded off, and is provided with an aperture 18 through which extends a smaller cylindrical tube 20 adapted to be disposed in the interior 22 of the barrel 10. One end of the cylinder 20 is secured by threads 24 to an apertured baffle plate or partition 26 provided in the interior of the barrel 10. The lower end of the cylinder 20 is secured in the aperture 18.

A centrally disposed valve cage 28 is secured to the cylinder 20 immediately above the baffle

26, and houses a ball valve 30 cooperating with a valve seat 32. The walls of the barrel 10, adjacent the cage 28, are provided with a plurality of circumferentially spaced apertures 34 for a purpose as will be hereinafter set forth. It will be apparent that the upper portion 13 can be uncoupled at 15 to allow replacement of the valve assembly.

Alluding further to the annular groove 16, each of the grooves are provided with an annularly inclined wall 36 and a horizontal wall 38. The walls 38 are provided with a recess 40 communicating with a plurality of inclined ports or apertures 42 extending to the outer periphery of the barrel 10.

In operation, the agitator is submerged in the fluid of the well hole, and is reciprocated vertically by the drill stem. On the downward stroke of the barrel 10, fluid in the well hole is allowed to displace through the cylinder 20 to move the ball valve 30 off its seat 32, wherein fluid passes through apertures 34 to be sprayed against the walls of the well hole 14. Upon an upward movement of the barrel 10, fluid passes into the annular grooves 16 and discharges through the apertures 42 to be sprayed against the wall 14 in order to dislodge, and wash down any loose particles of sand, paraffin, and the like, and cause the same to fall into the well hole below the agitator, to be bailed out in any conventional manner.

The reciprocatory motion of the agitator is usually very rapid, and its improved construction renders a forceful and effective spraying of the oil against the wall of the well hole 14 on both the upward and downward strokes of the agitator to assure a washing down of all loose particles of sand, and the like. It will be apparent that the valve 30 is seated during the upward stroke of the agitator.

It sometimes becomes necessary to rotate the barrel 10 for agitating the fluid, and in order to assist the agitation the annular grooves 16 (note Fig. 3) are provided with a plurality of ribs or braces 44 (preferably three in number) circumferentially spaced at approximately 120 degrees apart. In certain oil fields a liner screen is used in the well which often becomes blocked up by debris, and the like. The barrel 10 can be rotated whereby the ribs 44 will agitate the fluid for cleaning screens, and the like.

Changes may be made in the combination and arrangement of parts as heretofore set forth in the specification and shown in the drawing, it being understood that any modification in the

precise embodiment of the invention may be made within the scope of the following claims without departing from the spirit of the invention.

5. What I claim is:

1. In a well cleaning tool comprising a barrel adapted to be reciprocated in an oil well hole, a valve chamber in the barrel, means allowing displacement of fluid from the well hole to the 10 valve chamber, means for discharging the fluid from the valve chamber to the walls of the well hole, and means on the periphery of the barrel for spraying fluid against the walls of the well hole.
15. 2. In a well agitator comprising a tubular body having a valve assembly disposed in the interior thereof, an inner cylinder disposed in the tubular body providing communication between the valve assembly and the wall, lateral fluid outlets adjacent the valve assembly, a plurality of axially spaced annular grooves on the periphery of the body, and a plurality of apertures communicating with each of the grooves for spraying fluid outwardly from the tubular body.
20. 3. A tool for agitating liquid in an oil well comprising a tubular body adapted to be rotated in the well, a plurality of vertically spaced annular grooves arranged on the body, a plurality of circumferentially spaced ribs provided in each

of the grooves to assist agitation during rotation of the body, and a plurality of apertures communicating with each of the grooves for spraying fluid from the well against the walls of the well hole.

5. 4. In a cleaning tool comprising a barrel adapted to be reciprocated in an oil well hole, a valve chamber in the barrel, a cylinder disposed in the interior of the barrel and providing communication between the valve chamber and the well hole, means for discharging fluid from the valve chamber against the walls of the well hole upon a downward stroke of the barrel, and means arranged on the periphery of the barrel for spraying fluid against the walls on an upward stroke of the barrel.

10. 5. In a cleaning tool comprising a barrel adapted to be reciprocated in an oil well hole, a valve chamber in the barrel, a cylinder disposed in the interior of the barrel and providing communication between the valve chamber and the well hole, means for discharging fluid from the valve chamber against the walls of the well hole, means arranged on the periphery of the barrel for spraying fluid against the walls of the well 15 hole, and a plurality of circumferentially spaced ribs provided in the last mentioned means for agitating the fluid during rotation of the barrel.

JOSEPH H. NOTLEY. 30
